CLAIM

The ornamental design for an iron for straightening hair, as shown and described.

DESCRIPTION

1. Iron for straightening hair

FIG. 1.1 is a perspective view of an iron for straightening hair, showing my new design;

FIG. 1.2 is an end elevation view thereof;

FIG. 1.3 is a bottom plan view thereof;

FIG. 1.4 is another end elevation view thereof;

FIG. 1.5 is a side elevation view thereof;

FIG. 1.6 is a top plan view thereof;

FIG. 1.7 is another perspective view thereof;

FIG. 1.8 another side elevation view thereof.
